UNITED STATES PATENT OFFICE.

OSCAR ALAMO, OF NEW ORLEANS, LOUISIANA.

SANITARY COLLAR.

Application filed November 1, 1924. Serial No. 747,258.

To all whom it may concern:

Be it known that I, OSCAR ALAMO, a citizen of the United States, residing at New Orleans, in the parish of Orleans and 5 State of Louisiana, have invented certain new and useful Improvements in Sanitary Collars, of which the following is a specification, reference being had to the accompanying drawings.

10 This invention relates to certain improvements in sanitary collars and has relation more particularly to a device of this general character especially designed and adapted for use by barbers, and it is an object of the 15 invention to provide a device of this kind constructed in a novel and improved manner whereby it may be conveniently and effectively applied around the neck of a customer and which also serves to protect the customer 20 against friction or other annoyance incident to the general use of a towel or apron.

Another object of the invention is to provide a novel and improved device of this kind constructed in a manner whereby it 25 may be at all times maintained in a highly sanitary condition and which when in use affords an effective protection against hair clippings.

The invention consists in the details of 30 construction and in the combination and arrangement of the several parts of my improved sanitary collar whereby certain important advantages are attained and the device rendered simpler, less expensive and 35 otherwise more convenient and advantageous for use, as will be hereinafter more fully set forth.

The novel features of my invention will 40 hereinafter be definitely claimed.

45 In order that my invention may be the better understood, I will now proceed to describe the same with reference to the accompanying drawings, wherein:—

Figure 1 is a view in plan of a collar constructed in accordance with an embodiment 45 of my invention with the end portions of one of the members turned back;

Figure 2 is a view in perspective of the device as herein disclosed;

50 Figure 3 is a fragmentary transverse sectional view.

As herein disclosed, my improved collar comprises two superimposed annular members 1 of requisite dimensions having the

inner edges thereof connected by a selvedged 55 tape 2. The members 1 are preferably formed of rubber and are intersected by a radial cut or slit 3, the resultant end edges of the members 1 and the peripheral edges thereof being protected by a selvedged tape 60 4 secured thereto in a conventional manner.

Secured to the inner face of one of the members 1 at a point in close proximity to its connection with the second member is the intermediate portion of a tape 5. This 65 tape 5 is connected to said member 1 from one end of said member to a point slightly beyond the center thereof. The free end portions α of this string 5 are of sufficient length to readily permit the collar to be 70 properly tied in working position.

In practice, my improved collar is disposed around the neck of a customer, the particular engagement of the string 5 with a member 1 readily permitting said collar 75 to be adjusted as the requirements of practice may necessitate. The towel or apron as now generally employed by a barber has its upper marginal portion disposed between the members 1 whereby the necessity of forcing the towel or apron inwardly of the collar 80 of the shirt of the customer is avoided and thereby eliminating friction or other annoyance incident to the common use of such towel or apron.

85 After the barber has completed the service, the collar may be readily removed and properly sterilized to maintain the same in a highly sanitary condition.

90 From the foregoing description it is thought to be obvious that a sanitary collar constructed in accordance with my invention is particularly well adapted for use by reason of the convenience and facility with which it may be assembled and operated, and 95 it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

100 I claim:—

As a new article of manufacture, a collar for use by a barber comprising two superimposed annular members, means for con-

105

necting the inner margins of said members, said members being split transversely there-across, and a tie string disposed between said annular members and having an intermediate portion thereof secured to one of the members from an end of one of said members to a point slightly beyond the cen-

ter of said member, said connected portion of the tape extending along said member in close proximity to its inner margin.

In testimony whereof I hereunto affix my signature.

OSCAR ALAMO.
